UNITED STATES PATENT OFFICE.

JOHN CARL POETZ, OF LEONIA, IDAHO.

FOUNTAIN PEN.

Application filed November 14, 1925. Serial No. 69,040.

My present invention relates to improvements in fountain pens of the self filling type and employing a piston mechanism for filling the barrel. The piston is reciprocable 5 in the barrel, and the stem which is detachable from the piston for normal use, is utilized in connection with the piston for filling the barrel in a facile and convenient manner. Means are provided whereby leakage is avoided and the filling device is well sealed for use of the pen, and the parts may 10 readily be manipulated in the filling operation. The fountain pen as constructed according to my invention is comprised of a practical minimum number of parts, is durable, and may be manufactured at a comparatively low cost of production.

The invention consists in certain novel features of construction and combinations 20 and arrangements of parts in the filling device of the pen as will hereinafter be more fully set forth and claimed.

In the accompanying drawings I have illustrated one complete example of the physical embodiment of my invention wherein the parts are combined and arranged in accordance with the best mode I have thus far devised for the practical application of the principles of my invention.

30 Figure 1 is a vertical longitudinal section of the pen with some parts in elevation, showing the parts in normal position with the pen filled.

Figure 2 is an enlarged sectional view 35 showing the plug-handle withdrawn as when filling the pen, and in closed dotted position.

Figure 3 is a detail sectional view at line 3—3 of Fig. 2.

In the preferred form of my invention as 40 illustrated in the drawings I utilize a cylindrical barrel 1 of suitable material and size to which is attached the head 2 of the pen which is provided with the usual pen point 3. The feed of ink from the barrel to the 45 pen point is through ducts 4 in the head 2, and the barrel is also filled, by suction, through these ducts when the head of the pen is immersed in the supply of ink.

The pen is filled with ink through the 50 manipulation of a reciprocable piston 6 which conforms to the cylindrical interior of the barrel and is designed to be reciprocated therein, first to force out any ink that may remain in the barrel for cleansing purposes, and then to draw in a fresh supply 55 of ink through the ducts 4 by the action of

suction. The piston is provided with an annular exterior groove 7 in which a packing ring 7' is located to prevent passage of ink along the piston surface, and a rubber 60 gasket 8 is also attached to the piston for contact with the inner wall of the cylinder or barrel to prevent leaks.

The gasket is secured on the end of the piston by means of a metal plate or retainer 9, and the plate and gasket are fastened to the piston by means of a suitable number of screws or pins 10 which pass through the plate and gasket and are secured in the piston.

In its normal position at the upper end of the barrel, the piston is held against rotation therein by the co-action of an exterior longitudinal groove or socket 11, and a retaining pin 12, the latter fixed in the wall of the barrel and projecting radially therein to occupy the space of the groove 11. In Figure 2 it will be seen that the groove extends through a portion of the piston and also through the gasket and its retaining plate to permit the piston to be pushed or moved from its normal position in full lines Figure 2 to its dotted position in this figure. The retaining pin however prevents the piston from being pulled upward to the extreme upper open end of the barrel.

The piston is provided with a central longitudinal opening to accommodate its detachable stem 13 which is supported therein under normal conditions as indicated in Figure 1. At its inner end the stem is fashioned with an enlarged head 14 which is threaded at 15 to engage complementary threads in a socket 15' of the piston. At the junction of the head with its stem a conical valve portion 16 is provided which engages a complementary seat 17 fashioned in the longitudinal opening of the piston, to prevent passage of ink through the piston.

At its outer end the stem is provided with a plug-handle or knob 18 having a socket therein for the end of the stem, and the plug-handle or knob is secured on the stem by means of a transversely extending retaining pin 19.

To insure a close fit of the plug-handle within the upper end of the barrel, the plug is cut away, grooved, or undercut as at 20, and a shoulder 21 is thus formed on the plug to engage over the end of the barrel. By this means of the annular groove on the plug and its shoulder, the plug, in normal

position is rigidly retained within the end of the barrel by the frictional engagement of the plug and barrel, and the stem which is rigid with the plug is maintained in its normal position of Figure 1.

As an additional means for securing a leak-proof joint of the stem in the piston, the plug-handle is fashioned with a central boss 22 which, when in normal position fits 10 neatly into a central opening 23 in the metal retaining plate 9 and bears against the exposed central portion of the rubber gasket 8 to compress the latter about the stem.

In Figure 1 the pen is illustrated as substantially filled with ink and with its parts in position for use. When the pen is empty and the supply of ink is to be replenished, the plug-handle is grasped by the fingers and thumb and pulled from the end of the barrel, 15 thus pulling the head of the stem into the socket of the piston. Then the stem is rotated to engage the threads of the head in the threaded socket, the pin 12 and groove 11 co-acting to prevent turning of the piston. 20 After the head is screwed into the piston and thus attached thereto, the piston is pushed down in the barrel by pressure on the plug-handle to eject air and any ink remaining in the barrel through the ducts 4 25 of the pen-head. Then by reversing the movement of the piston by a pulling action on the plug handle, and with the pen head immersed in an ink supply, it will be apparent that a supply of ink is drawn by suction 30 into the barrel for filling the same. After the barrel has been filled and with the piston retained against rotation in its normal position of Fig. 2 the plug handle is turned to 35

unscrew the head 14 from the piston and the stem is then pushed into normal position of Figure 1. In this position the plug handle closes the upper end of the barrel and makes a tight joint between the stem and piston to prevent leaks.

Having thus fully described my invention, what I claim as new and desire to secure by Letters Patent is—

1. The combination with a barrel having a laterally projecting retaining pin therein and a piston having an exterior transverse groove for co-action therewith, of a stem and means for detachably connecting said stem and piston, a gasket and an open center retaining plate on the piston, a plug handle on the stem adapted to seat in the end of the barrel, and a boss on said plug-handle adapted to seat within the retaining ring for engagement with said gasket.

2. In a fountain pen, the combination with a piston having an exterior, transverse groove, a central threaded socket and an aligned opening through the piston, of a barrel having a laterally projecting retaining pin therein for co-action with the groove of the piston, a stem reciprocable in the piston and an enlarged threaded head on the stem for engagement with said socket, a gasket and an open center retaining plate on the piston, a plug handle on the stem adapted to seat in the end of the barrel, and a boss on the plug handle adapted to seat within the retaining ring for engagement with said socket.

In testimony whereof I affix my signature.

JOHN CARL POETZ.
